UNITED STATES PATENT OFFICE.

HARRY W. McDONALD, OF CHICAGO, ILLINOIS.

COMMUNICATION-SHEET.

No. 830,354.

Specification of Letters Patent.

Patented Sept. 4, 1906.

Application filed August 14, 1905. Serial No. 274,048.

To all whom it may concern:

Be it known that I, HARRY W. McDONALD, a citizen of the United States, residing at Chicago, county of Cook, State of Illinois, have invented a certain new and useful Improvement in Communication-Sheets; and I declare the following to be a full, clear, and exact description of the invention, such as will enable others skilled in the art to which it pertains to make and use the same, reference being had to the accompanying drawings, which form a part of this specification.

My invention relates in general to sheets of letter-paper, and more particularly to letter-sheets adapted for transmission without the use of envelops.

In order that time, labor, and expense of addressing envelops may be saved, envelops are sometimes provided with trans- 20 parent portions through which the name and address of the sendee on the inclosed sheet of paper may be exposed to serve as the address for the envelop. It has also been proposed heretofore to avoid the expense of 25 envelops and the labor of inserting sheets of paper therein to provide combined letter-sheets and envelops adapted to be so folded that the name and address of the sendee on the sheet of paper will be exposed and serve as the 30 direction for the transmission of the letters.

The primary object of my invention is to provide an improved letter-sheet adapted to be so folded that the name and address of the sendee will serve both as the heading 35 of the communication and as the direction for its transmission, thereby avoiding the use of an envelop, as well as rendering it unnecessary to separately address the letter-sheet.

A further object of my invention is to pro- 40 vide a sheet of letter-paper adapted to be transmitted without the use of an envelop which will be simple in construction, inexpensive in manufacture, and convenient in use.

The several embodiments of my invention herein disclosed may be generally described as consisting of a sheet of letter-paper comprising a plurality of transverse sections, the top section adapted to have inscribed thereon the name and address of the sendee, the lower section adapted to contain the body of the communication, and the bottom section being cut away so that when the sheet is folded for transmission the bottom section will overlie the top section, except the portion thereof containing the name

and address of the sendee, which will be exposed.

My invention will be more fully described hereinafter with reference to the accompanying drawings, in which the same is illustrated as embodied in several convenient and practical forms, and in which—

Figure 1 is a plan view of the sheet unfolded; Fig. 2, a plan view of the sheet shown in Fig. 1 folded for transmission; Fig. 3, a plan view of a modified form of sheet unfolded; Fig. 4, a plan view of the sheet shown in Fig. 3 folded for transmission; Fig. 5, a plan view of still another modified sheet unfolded, and Fig. 6 a plan view of the sheet shown in Fig. 5 folded for transmission.

Similar reference characters are used to designate similar parts in the several figures of the drawings.

Referring more particularly to Figs. 1 and 2, reference-letter A indicates the upper section of a sheet of letter-paper comprising four horizontal sections. The upper portion of the top section A is adapted to have inscribed thereon the name and address of the party to whom the communication is directed. The following sections B, C, and D afford space for having written thereon the body of the letter, bill, statement, or the communication. The lower section D is cut away so as to have a smaller vertical dimension than the other sections. d d indicate ears or flaps projecting laterally from the section D. The sheet of paper above described when prepared for transmission is first folded along the line b b, so the section C overlies the section B, while the section D overlies the portion of the section A which does not contain the name and address of the sendee. The sheet of paper is then folded along the lines a a and c c, which are superposed. The ears d d are then folded around the edges of the sections and secured to the outer surface of the section C. The ears d d may conveniently be provided with adhesive or the adhesive may be provided on the surface of the section C which is engaged by the ears. If desired, the lower section D may be provided with a transparent strip of material E, corresponding to the portion of the section A containing the name and address of the sendee, so that when the sheet of paper is so folded as to superpose the sections the transparent material will cover, but will permit the reading of, the name and address of sendee. The transparent material E may

be provided with a flap *e*, adapted to be folded around and secured to the outer surface of the section *C*.

In Figs. 3 and 4 I have illustrated another embodiment of my invention, which is similar in all respects to that above described, as illustrated in Figs. 1 and 2, except that the lower section *D'* is not cut away along a horizontal line, but has a vertical dimension at each side substantially the same as the vertical dimension of the other sections and is cut away along a line running upwardly from the lower edge of the section near each side thereof, so as to expose the name and address of the sendee on section *A'* when the sheet is folded for transmission. If desired, the lower section *D'* may be provided with a transparent piece of material *E'* to cover the portion of the section *A'* which is not covered, owing to the cut-out portion of the section *D'*.

In Figs. 5 and 6 I have illustrated still another embodiment of my invention, in which the horizontal sections *A²*, *B²*, *C²*, and *D²*, after being folded along horizontal lines so as to be superposed, are then adapted to be folded along a vertical line. In this embodiment of my invention the name and address of the sendee are to be placed at the left of the upper section *A²*, while the left of the lower section *D²* is cut away, so as to expose the space on the section *A²* containing the name and address of the sendee when the sheet of paper is folded for transmission. The lower section *D²* is provided with flaps *d²* at the bottom of the right portion thereof and a side flap *d³*, which when the sheet of paper is folded overlie the front of the letter which comprises the section *D²* and the exposed portion of the section *A²*. The cut-away portion of the section *D²* may be provided with a transparent piece of material *E²* to cover the portion of the section *A²* containing the name and address of the sendee.

The several embodiments of my invention may or may not be provided with pieces of transparent material within the cut-out portion of the lower sections, and such transparent material may be either secured to the sheets of paper or they may be rendered transparent by suitable treatment throughout the desired portions thereof.

From the foregoing description it will be observed that I have invented an improved sheet of letter-paper by means of which the need of envelops is avoided and which does not require a separate address for the transmission of the letter, the name and address of the party to whom the communication is directed being exposed when the sheet is folded, so as to afford the necessary information to transmit the letter to its destination.

It is evident that the bottom section may contain the conclusion of the body of the

communication or it may serve as a covering which may be detached in order to open the letter by severing the same from the adjoining section and also by severing the side flaps.

The term "letter-sheet" as used throughout the specification and claims is intended to cover not merely sheets of paper to be used for letters, but any sheets of paper for transmitting communications of all kinds.

Having now fully described my invention, what I claim as new, and desire to secure by Letters Patent, is—

1. A communication - sheet comprising a plurality of transverse sections adapted to be folded upon each other, the upper section having a space for the name and address of the sendee, the lower sections affording space for the body of the communication, said spaces on the upper section for the name and address of the sendee and on the lower sections for the body of the communication being on the same side of the sheet, said bottom section when the sheet is folded with the surface containing the body of the communication inside terminating below the space of the top section containing the name and address of the sendee, whereby a single inscription of the name and address of the sendee serves both as the heading of the communication and the direction for its transmission.

2. A communication-sheet comprising a plurality of sections adapted to be folded upon each other, the upper section having a space for the name and address of the sendee, the lower sections affording space for the body of the communication, and the bottom section terminating when the sheet is folded below the space of the top section containing the name and address of the sendee, and a transparent piece of material secured to the bottom section and adapted to cover the space of the top section containing the name and address of the sendee.

3. A communication-sheet comprising a plurality of transverse sections adapted to be folded upon each other, the upper section having a space for the name and address of the sendee, the lower sections affording space for the body of the communication, and the bottom section adapted to overlie the top section and having a portion extending from one edge cut away to expose the space on the top section containing the name and address of the sendee.

4. A communication-sheet comprising a plurality of transverse sections adapted to be folded upon each other, the upper section having a space for the name and address of the sendee, the lower sections affording space for the body of the communication, and the bottom section adapted to overlie the top section and having a portion extending from one edge cut away to expose the space on the top section containing the name

and address of the sendee, and a transparent piece of material secured to the bottom section and filling the cut-out portion thereof.

5. A communication-sheet comprising a plurality of transverse sections adapted to be folded along horizontal lines upon each other and the superposed sections then folded along a vertical line, the upper section having a space at the left thereof for the name and address of the sendee, the lower sections affording space for the body of the communication, and the bottom section adapted to overlie the top section and having a portion at the left thereof cut away to expose the space on the top section containing the name and address of the sendee.

6. A communication-sheet comprising a plurality of transverse sections adapted to be folded along horizontal lines upon each other and the superposed sections then folded along a vertical line, the upper section having a space at the left thereof for the name and address of the sendee, the lower sections affording space for the body of the communication, and the bottom section adapted to overlie the top section and having a portion at the left thereof cut away to expose the space on the top section containing the name and address of the sendee, and a transparent strip of material secured to the bottom section and filling the cut-out portion thereof.

7. A communication-sheet comprising a plurality of sections adapted to be folded upon each other, one section having a space for the name and address of the sendee, and a second section adapted to overlie the first section and being cut away from an edge thereof to expose the space on the first section for the name and address of the sendee.

40 8. A communication-sheet comprising a

plurality of sections adapted to be folded upon each other, the upper section having a space for the name and address of the sendee, the lower sections affording space for the body of the communication, and the bottom section terminating when the sheet is folded below the space of the top section containing the name and address of the sendee, and a transparent piece of material attached to the bottom section and adapted to cover the space of the top section containing the name and address of the sendee.

45 9. A communication-sheet comprising a plurality of sections adapted to be folded for transmission, one section being cut away from an edge thereof to expose the portion of an underlying section adapted to contain the name and address of the sendee.

50 10. A communication-sheet consisting of a plurality of sections adapted to be folded for transmission, one section having space thereon to contain the name and address of the sendee, and another section having a space for the body of the communication, said spaces on said sections for the name and address of the sendee and for the body of the communication being on the same side of the sheet, said second section when the sheet is folded with the surface containing the body of the communication inside terminating relatively to the first-named section to disclose the space thereon containing the name and address of the sendee.

55 In testimony whereof I sign this specification in the presence of two witnesses.

HARRY W. McDONALD.
